COMBINATION BED AND DAVENPORT
Irvin C. Poskin, 1828½ S. Robertson Blvd.,
Los Angeles 35, Calif.
Filed Oct. 23, 1962, Ser. No. 232,444
5 Claims. (Cl. 5—41)

This invention relates to a combination bed and davenport together with useful adjuncts combined therewith.

Objects of the present invention are: so to construct a davenport of the kind described as to enable a salesman in a crowded store more conveniently to demonstrate the merits of the device. For this purpose a track is provided which removably rests upon the floor, and the davenport is provided with track wheels to travel on said track, rendering it movable out from a wall to a position for being inspected from all sides. Said track is an adjunct to the davenport and is automatically picked up thereby when the davenport is moved back to its normal position by a wall.

The track provided by this invention renders the wheel-supported davenport more freely movable across a floor and protects from wear the floor or its covering.

Additional objects, advantages and features of invention will hereinafter appear.

Referring to the accompanying drawings, illustrative of a preferred, reduced to practice embodiment of the invention,

FIG. 1 is a perspective view of the complete device, showing it adjusted to the davenport position, a portion of the cushion being broken out to show underlying structure.

FIG. 2 is an elevation looking at the back side of the device positioned as shown in FIG. 1, the scale being somewhat enlarged.

FIG. 3 is a perspective view of the device showing it adjusted to bed forming position.

FIG. 4 is an enlarged cross-section showing the swingable back in its up-swinged position, together with adjacent structure, the plane of section being on line 4—4 of FIG. 2, parts being omitted to simplify the view.

FIG. 5 is a sectional detail, on line 5—5 of FIG. 2, illustrating the foot operable release which is operated when the device is changed from a davenport to a bed, or from a bed to a davenport.

FIG. 6 is a plan of the device adjusted to the davenport position with the davenport moved out from a wall, disclosing the track which forms part of the device. In this view the cushions, bed springs and davenport back are omitted.

FIG. 7 is a sectional end elevation showing the device adjusted to the davenport forming position.

FIG. 8 is a fragmental elevation illustrating one of the roller carrying feet and its relation to a supporting track.

FIG. 9 is a section on line 9—9 of FIG. 8.

FIG. 10 is a fragmentary perspective illustrating the foot operable means for releasing the davenport back.

FIG. 11 is an end view of the device, partly in elevation and partly in section, moved out from a wall and adjusted to bed forming position.

FIG. 12 is an enlarged fragmentary sectional view on line 12—12 of FIG. 11, illustrating the catch which maintains the device in the davenport forming position.

FIG. 13 is a fragmentary vertical section on line 13—13 of FIG. 6.

FIG. 14 is a plan view in perspective, showing the track on which the rear portion of the structure is movable toward and from a wall.

FIG. 15 is a perspective view illustrating the handle-carrying rod of the lock release means which, when desired, can be used instead of the foot-operable release means.

2

Referring in detail to the drawings, the body portion of the davenport comprises a basal, rectangular, skeletal frame 20 having, spaced forwardly from its rear side, an additional side beam 21. Mounting blocks 22 for parts hereinafter described, are secured between said member 21 and the adjacent rear side 20x (see FIG. 7) of the frame 20. Each end portion of said davenport frame is also rectangular, and comprises a horizontal top member 24, horizontal basal member 25, L-shaped in cross-section, and upstanding front and rear members 26 and 27. Also, across the lower portion of each end frame extends a mounting and reinforcing member 29.

In an upwardly spaced relation to the tubular pivot 66 about which it swings the davenport back 30 has swingably attached to each of its end portions by means of a pin 31a, a strap metal leg 31 which closely overlies its back surface when not in use, but with which is combined a swingably mounted link 32 which causes the leg to swing out to the operative position when the device is adjusted to the bed forming position, shown in FIG. 11. The inner end portion of each of the links 32 is swingably attached by a pin 32a to a fastening plate 33 secured to the frame member 27. This structure is shown and described in my Patent No. 2,636,187, and separately considered, 25 forms no part of the present invention.

A rectangular track member 35 underlies the davenport when it is positioned close to a wall. This member comprises two angle iron track rails 36 joined rearwardly by an angle iron 37 and forwardly by an angle bar 38. 30 To said bar is attached a pair of forwardly directed, upwardly inclined fingers 39. With these fingers co-operates a longitudinally extending pick-up rod 40 carried at its ends by brackets 40b mounted on transverse members 41 which extend from front to rear of the lower portion of the davenport.

The forwardly and rearwardly extending angle iron track rails 38 are supported by the basal angle iron rails 37 and 38. The rear basal rail 37 has a basal flange 37a with its width extending horizontally. A foot 37f, which is welded to each end portion of said flange 37a, normally supports said rail 37 slightly spaced above the floor. One flange 38a of the front basal rail 38 has its width extending vertically with its lower edge at times engaging the floor, thus efficiently preventing the track from sliding upon the floor. The lower rear portion of the davenport is provided near each of its ends with a caster 42 and a pair of casters 42a. The caster 42 travels along the upper surface of the lower rail flange 36, and the casters 42a engage the inner side of the vertical flange of the rail to keep the structure of which it forms a part from being laterally displaced from that side. Each front corner portion of the davenport carries a large floor engaging caster 42c.

The track structure is preferably provided at its rear side with a pair of buffer carrying arms 42b, which prevent the track from being moved too close to a wall.

The casters 42a (see FIGS. 8 and 9) are carried by U-shaped clips 42x which are welded or otherwise secured to angular brackets 42y having horizontal flanges secured by screws to the basal portion of the davenport.

As typically illustrated in FIG. 9 each of the four upstanding track ears 44 is beveled at 44x automatically to direct each locking pin into the aperture of the ear at the proper time.

65 When the davenport is positioned near a wall it is near each rear corner, attached to the aforesaid track by means of a locking pin 43 which co-operates with aforesaid apertured ear 44 carried by and upstanding from the track (see FIG. 9). Each of said locking pins is slidably carried by an elongated housing 45 furnished with a cross-wall 46. Around each pin is loosely coiled a compression spring 47 which acts between said cross-

wall and a collar 43c carried by the pin 43 to urge the pin toward locking position. The means for manually retracting said pin from its locking position comprises a wire rod 50 (FIG. 6) having one end axially secured to the pin, and its opposite end fastened to one end of a lever or link 51 (see lower part of FIG. 2) the mid-length portion of which is secured to a manually turnable shaft 52. Said shaft 52, in turn, is secured to the mid-length portion of a primary lever 53 (see FIG. 13). One end of this lever has fastened to it an upstanding pull rod 54, the upper end of which is connected with a yoke 55. A block 56 secured to the adjacent portion of the frame, is positioned to form a stop for the swinging movement of said lever 53. Said yoke 55 is furnished with a handle portion 57, which is grasped by the operator and pulled upwardly to operate the pin releasing mechanism just described, thus to release the track from the davenport preparatory to pulling the latter out from the wall.

When the davenport is moved forwardly to limit of its travel the aforesaid pins 43 interlock with apertured ears 44a upstanding from the front portions of the track rails, to releasably lock the track to the davenport, so as to maintain the latter stationary in the desired bed forming position.

A foot operable means is provided to release the davenport back, this means comprising an L-shaped pedal member 60 the vertical limb 61 of which extends slidably through the already mentioned lower crosspiece 25 of the davenport. A flexible connection 62 connects said limb 61 with one arm 63 of a rockable rod 64 of a rectangular U shape, which is swingably mounted upon the crosspiece 29 of the davenport frame. To the other arm 63a of said rockable member is connected a wire pull rod 68 which is, in turn, connected to a pin 69 (FIGS. 10 and 15) which projects rightangularly from a shaft 70 which is carried by bearing members 71 and 72.

Said pull rod 68 extends slidably through a tubular bearing pin 66, which co-operates with a bearing pin (not shown) at the opposite side of the structure, swingably to mount the davenport back.

Dual means having parts in common are provided for releasing the back of the davenport. One of these comprises aforesaid manually turnable shaft 70 mounted upon the back and extending thereacross adjacent thereto. This shaft is shown in FIGS. 2 and 15 provided at its upper end with a rightangularly projecting handle 70a, which, together with the parts it operates, is shown and described in my Patent No. 2,515,261, these parts also being described hereinafter.

The already mentioned casters 42 and 42c support the davenport frame with its basal portion spaced sufficiently above the floor to provide room for operating the pedal 60 shown in FIG. 10 with its upstanding part extending slidably through the horizontal portion of the frame member 25.

By preference and as shown in FIG. 2, the present embodiment of the invention is provided with manually operable release means some features of which are shown in my said Patent No. 2,997,340. This release means comprises, in addition to the already mentioned shaft 70, a cross lever 75 (see FIGS. 2 and 12) to one end of which is connected a wire pull rod 76, and to the opposite end of which is connected a wire pull rod 77, both these rods functioning in a similar manner. These rods are respectively provided with tension springs 78a and 77a. Each of these rods is secured to the free end portion of a locking dog 78. Said dog swings about a pivot 79 and is of a bell-crank shape, a compression spring 80 being provided to urge it toward locking position. Said dog co-operates with a notch 81 in aforesaid plate 33 to hold the davenport back in a down position in opposition to twin springs 82 (FIG. 1) which tend to swing the back to the upright position. These springs are shown in my aforesaid patent.

Mentioning briefly the additional manually operable means for releasing the davenport back for downswing-

ing, shown in FIG. 2 and described in my Patent No 2,636,187, the aforesaid shaft 70 is provided with an additional cross-lever 85, having its end portions connected with rods 86 and 87 and connected to twin locking devices 88.

A sturdy mounting of the swingable back 30 results from the tubular pivot 66 extending through an end piece 30a of the back and also through a block 30b secured to said end piece as shown in FIG. 10.

Operation.—Assuming the device to be located near a wall in the davenport position shown in FIG. 1, when it is desired to change to the bed forming position the operator pulls upwardly on the U-shaped member 57 shown in the break in FIG. 1, thus pulling the track supporting pins 43 (see FIG. 9) to the release position. Then the davenport will be pulled out from the wall, the rear casters 42 and 42a travelling to the front end of the track while the front casters 42c travel on the floor, the davenport being thus moved far enough from the wall to allow it to be converted into a bed.

When, owing to moving the davenport away from the wall, the locking pins 45 reach the front track ears 44a they glide over the beveled portions of said ears into the apertures of the ears and releasably lock the davenport to the track so that, after it has been converted into a bed it remains stationary in the desired position.

When the davenport is moved back nearly to its original position the pick-up rod 40 (see FIGS. 11 and 13) passes under the upwardly deflected front end portions of fingers 39, and at the same time, as the davenport concludes its rearward movement, the spring loaded pins 43 (see FIG. 9) glide over the beveled portions 44x of the rear clips 44 and then enter the apertures provided for them in said clips, making a stable, dual connection of the track with the davenport.

So far as I am aware the aforesaid track structure and the manually operable release means associated therewith is basically novel and may be advantageously applied to various bed and davenport structures beside that which has been illustrated and described.

Although a preferred embodiment of the invention has been illustrated and described, yet it is to be understood that changes therein, within the scope of the claims may be made without departing from the spirit of the invention.

I claim:

1. The combination, with a combined davenport and bed having a swingable back adjustable from an upstanding to a downswung position, and front and rear casters; of a track member which, when the davenport back is in an upstanding position normally underlies the davenport with said rear casters engaging the rear portion of said track, track attaching means which at such time releasably connect both the front and rear portion of said track member with the davenport, and manually operable means carried by the davenport and operable to release the rear portion of said track therefrom, the front portion of the davenport being slidably related to said track member so that, after said manually operable track release means has been operated the davenport may be moved forwardly over said track till said rear casters reach its front portion, while said track member remains stationary upon a floor.

2. The subject matter of claim 1, and the means whereby the davenport is slidably related to the front portion of said track comprising upwardly inclined fingers projecting forwardly from the front portion of the track, and a horizontal rod carried by the davenport and normally underlying said fingers.

3. In an article of furniture of the kind described, a frame having a basal portion, a front pair and a rear pair of casters carried by said basal frame portion, a track member underlying said basal frame portion and normally attached thereto, said track member comprising a rail along each side in an operative relation to one or the other of the casters of said rear pair, an apertured

ear upstanding from each end portion of each of said rails, and spring loaded manually releasable locking pins carried by said basal frame portion, said ears having beveled portions adjacent to their apertures automatically to guide said pins into a locked relation to said apertures whenever said rear casters move along said track either forwardly or rearwardly to the limit of their travel.

4. The subject matter of claim 3, and said front casters being at all times located forwardly of said track member in a position to travel along a floor upon which the track member rests.

5. In an article of furniture of the kind described, a frame having a basal portion, a front and rear pair of casters carried by said basal frame portion, a track member normally underlying said basal frame portion in an attached relation thereto, said track member comprising a rail along each side in an operative relation to one or the other of the casters of said rear pair, an apertured ear upstanding from the rear end portion of each of said rails, spring loaded manually releasable locking pins carried by the rear portion of said basal frame portion, said ears having beveled portions adjacent to their apertures automatically to guide said pins into a locked relation to said apertures whenever said rear casters move

along said track rearwardly to the limit of their travel, and a horizontal pickup rod carried by the front part of said basal frame, said track member having at its front end forwardly directed upwardly inclined fingers under which said rod glides when the caster carrying member approaches the limit of its rearward travel.
